(57) **CLAIM**

The ornamental design for a lighting filtering device, as shown and described.

DESCRIPTION

FIG. 1 is a perspective view of a first embodiment of a lighting filtering device showing my new design in a state of use;

FIG. 2 is a perspective view of my design;

FIG. 3 is a front elevation view of my design;

FIG. 4 is a rear elevation view of my design;

FIG. 5 is a right-side view of my design;

FIG. 6 is a left-side view of my design;

FIG. 7 is a top plan view of my design;

FIG. 8 is a bottom plan view of my design;

FIG. 9 is a perspective view of a second embodiment of a lighting filtering device showing my new design in a state of use;

FIG. 10 is a perspective view of my design;

FIG. 11 is a front elevation view of my design;

FIG. 12 is a rear elevation view of my design;

FIG. 13 is a right-side view of my design;

FIG. 14 is a left-side view of my design;

FIG. 15 is a top plan view of my design; and,

FIG. 16 is a bottom plan view of my design.

The broken lines are for illustrative purposes only and form no part of the claimed design.

1 Claim, 10 Drawing Sheets
